UNITED STATES PATENT OFFICE.

CHARLES H. BEELER, JR., OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 20,103, dated August 12, 1890.

Application filed July 21, 1890. Serial No. 359,442. Term of patent 14 years.

To all whom it may concern:

Be it known that I, CHARLES H. BEELER, Jr., a citizen of the United States, and a resident of Philadelphia, Pennsylvania, have invented a new and original Design for a Font of Printing-Type, of which the following is a specification.

My design for a font of type is clearly shown in the annexed typographical impression.
10 The general appearance of the type is that of a block-letter, having a light face and heavily shaded at one side and at the base. The letters, with the exception of the letter I and the figure 1, are outlined from a cube. The face
15 of each letter is outlined by a white line and is shaded by line-shading. The upper edge

as well as the left-hand edge of each letter has a narrow dark line, but the left-hand side of the letter, as well as the base, is shaded with a heavy dark line. The numerals are 20 in keeping with the letters of the font.

I claim—

The design for a font of type, as described, and as shown in the annexed typographical impression.

In testimony whereof I have signed my name to this specification in the presence of two subscribing witnesses.

CHARLES H. BEELER, JR.
